UNITED STATES PATENT OFFICE.

NELSON WITTS, OF ALMA CITY, MINNESOTA.

SNOW-PLOW.

SPECIFICATION forming part of Letters Patent No. 252,639, dated January 24, 1882.

Application filed December 5, 1881. (No model.)

To all whom it may concern:

Be it known that I, NELSON WITTS, of Alma City, in the county of Waseeo and State of Minnesota, have invented certain new and useful Improvements in Snow-Plows; and I do hereby declare that the following is a full, clear, and exact description of the invention, which will enable others skilled in the art to which it appertains to make and use the same, reference being had to the accompanying drawings, which form a part of this specification.

The object of this invention is to provide an improved snow-plow which will readily cut its way through deep and compact snow-drifts, and which will clear the snow from the rails and throw it to the sides of the track. These objects I attain by means of the devices illustrated in the annexed drawings, in which—

Figure 1 is a top or plan view of the principal part of a snow-plow embodying my invention. Fig. 2 is a side elevation, and Fig. 3 represents a modification.

In carrying my invention into effect I employ two large augers, A and B, arranged at the sides of a wedge-shaped projection, C, which is provided with curved edges C' and boxes C² at its rear ends, the lower edge of which boxes project laterally to form horizontal cutters C³, the whole constituting the front end of the plow. These augers converge toward their forward ends and have their shafts or axes supported in suitable bearings. The rear ends of the auger shafts will be provided with gears C, which intermesh with gear-wheels D, that can be driven by a system of gears connected with the engine, or by any suitable arrangement of pilot-wheels and belts or cranks and connecting-rods. The augers are caused to revolve about their respective axes as the plow advances, and they will cut into the snow and throw the same from off the rails. In this construction the wedge-shaped part of the plow

will prove serviceable in cutting through deep drifts.

In the modification shown I dispense with the wedge-shaped front portion of the plow and make the augers very large and with a taper from rear to front, thus forming a wedge-shaped projection in front of the plow composed of two augers. In this case a suitable bar will extend out from the body of the plow and bearings for the shafts of the augers be secured to the forward end of said bar; or, in place of said bar, any suitable frame can be employed. The auger shown in said modification consists of a metal band wound spirally around a shaft, one edge of said band being turned up or flanged, as at E, so as to effectively throw off the snow.

I am aware of Patent No. 124,739 to O. Heggem, which shows a wedge-shaped projection, above which, on each side, are arranged rotary augers supported in a suitable hanging bracket situated above and independent of the wedge-shaped projection. The construction shown in this patent I do not wish to be understood as claiming as my invention, which consists only in the novel construction and arrangement of parts herein shown and specified.

Having thus described my invention, what I claim is—

As an improvement in snow-plows, the combination, with the wedge-shaped projection C, having curved edges C', and boxes C², having horizontal cutters C³, of the rotary augers A, B, situated in channels formed by the curved edges C', all arranged and operating substantially as herein shown and specified.

In testimony that I claim the foregoing as my own I have hereto affixed my signature in presence of two witnesses.

NELSON WITTS.
